UNITED STATES PATENT OFFICE.

EUGENE H. SLAGLE, OF ENNIS, TEXAS.

CARBON-REMOVING TOOL.

1,374,530.

Specification of Letters Patent. Patented Apr. 12, 1921.

Application filed September 28, 1920. Serial No. 413,274.

To all whom it may concern:

Be it known that I, EUGENE H. SLAGLE, a citizen of the United States, residing at Ennis, in the county of Ellis and State of Texas, have invented certain new and useful Improvements in Carbon-Removing Tools, of which the following is a specification.

This invention relates to new and useful improvements in carbon removing tools.

10 The purpose of the invention is to provide means for removing the carbon from the ring grooves of the pistons of internal combustion engines, and particularly for cleaning grooves of different widths.

15 In carrying out the invention a yoke-shaped member is provided at one end with a guide arm or jaw adapted to receive one side of a piston. On the other end of the member, a laterally directed scraper is arranged diametrically opposite the jaw so as to stand at right angles to the piston and engage in the grooves thereof. The member is made of resilient metal so as to cause the jaw and scraper to snugly embrace the piston. The scraper is arranged to present different widths of blades to fit different widths of grooves. By swinging the member arcuately the scraper blade cleans the groove. The member may have a compressing loop for pressing the piston rings into the grooves.

The invention will be more readily understood from a reading of the following specification and by reference to the accompanying drawings, in which an example of the invention is shown, and wherein:

Figure 1 is a plan view of a tool constructed in accordance with my invention and showing its normal configuration in dotted lines,

Fig. 2 is a side elevation of the same,

Fig. 3 is a front elevation of the scraper,

Fig. 4 is a cross sectional detail on the line 4-4 of Fig. 3, and

Fig. 5 is a plan view of the tool in position on a piston for pressing the ring into the groove.

In the drawings the numeral 10 designates a general yoke-shaped member preferably formed of a single piece of spring metal of the flat bar type. The member constitutes a handle for manipulating the tool. At one end the member is formed into an arcual loop 11, which also constitutes a hinge. One of the ends of the member is twisted at right angles and bent angularly

to form a V-shaped jaw 12. The outer end 13 of the jaw is rounded so as not to catch on the piston.

The other end or arm of the member terminates short of the end of the jaw and has an outwardly directed ear 14 bent at substantially right angles to the arm of the member. On the outer side of the ear a rectangular scraper 15 is centrally pivoted on a rivet 16. A spring washer 17 interposed between the head of the rivet and the scraper, holds the latter in frictional engagement with the ear, thus tending to maintain the scraper in the position to which it is rotated.

The scraper is positioned substantially diametrically opposite the crotch of the jaw 12. Radial scraper blades 18 extend from the edges of the scraper and are angular with their outer and side edges at substantially right angles to each other. These blades are each preferably of a different width, each having substantially the same width as the width of the particular groove to be cleaned thereby. For instance one blade is wide enough to fit a piston ring groove one-eighth of an inch wide; while one of the other blades has a width designed to fit a groove one-quarter of an inch wide. It is to be understood that the number of blades may vary and if desired two could be made of the same width.

In using the tool the scraper 15 is rotated to bring the proper blade 18 opposite the crotch of the jaw 12. The jaw is sprung away from the scraper so as to grasp the piston A in its ring groove B, as is shown in full and dotted lines in Fig. 1. This causes the blade 18 to firmly engage in the groove B. It is pointed out that the V-shaped jaw is always self centering, irrespective of the diameter of the piston.

After the tool is in position the carbon is removed by swinging the member around the piston, whereby the blade 18 standing radially, cuts the carbon by means of its angular edges. The resilient jaw yieldably holds the scraper blade in the groove and the work is quickly done and a clean job had.

When the groove has been cleaned the tool is removed and the piston ring C is slipped over the piston to the groove. It is often necessary to press the ring into the groove and this is sometimes difficult to accomplish because one side will spring out

when the other is forced in. By springing the jaw 12 away from the scraper, the loop 11 may be passed down so as to embrace the ring C as is shown in Fig. 5. It will be seen that the loop will embrace more than half of the circumference of the ring and by pressing the ends of the tool together the ring is forced into the groove. The tool may be rotated so that the loop will force the ring into the groove as it passes over the same.

What I claim, is:

1. In a carbon removing tool, a resilient yoke-shaped member having a jaw at one end, and a scraper pivotally mounted on the opposite end of the member opposite the jaw and having a plurality of blades.

2. A carbon removing tool for piston ring grooves including, a handle support, a spring jaw carried by the handle, and a laterally directed scraper pivoted on the handle support opposite the jaw and including a plurality of blades.

3. A carbon removing tool for piston ring

grooves including, a handle support, a spring 25 jaw carried by the handle, and a laterally directed scraper pivoted on the handle support opposite the said jaw and including a plurality of blades, the blades being of different widths to fit grooves of different widths. 30

4. A carbon removing tool for piston ring grooves including, a handle support, a resilient V-shaped jaw carried by the support, and a laterally directed scraper pivoted on the support opposite the crotch of the said 35 jaw and including a plurality of blades of different widths.

5. A carbon removing tool for piston ring grooves including, a resilient loop, a V-shaped jaw carried by one end of the loop, 40 an arm extending from the other end of the loop, a scraper pivoted on the outer end of the arm opposite the crotch of the jaw, and radial blades of different widths extending from the scraper.

In testimony whereof I affix my signature.

EUGENE H. SLAGLE.
